UNITED STATES PATENT OFFICE

HENRY E. OLSEN, OF CHICAGO, ILLINOIS, ASSIGNOR TO W. G. LLOYD COMPANY, OF CHICAGO, ILLINOIS, A CORPORATION OF ILLINOIS

BINDER

Application filed January 23, 1931. Serial No. 510,798.

This invention relates to binders and particularly binders in which an adjustable clamping member is secured to a binder post.

The primary object of the invention is to provide an improved device for adjustably locking the adjustable clamping member or members to the binder posts. Other objects and advantages will appear as the specification proceeds.

10 The invention is fully described in the following specification and shown in the accompanying drawing, in which—

Figure 1 is a perspective view of a binder embodying my invention;

15 Figure 2 is an enlarged sectional view showing the locking member in engagement with a binder post;

Figure 3 is a similar sectional view showing the locking member out of engagement 20 with the post; and

Figure 4 is a magnified sectional and detail view, the section being taken, as indicated, at line 4 of Fig. 2.

In the embodiment illustrated, A represents the lower clamping member and B the upper clamping member. The members A and B may be provided with backs or covers A' and B' which may be secured to the clamping members by a flexible fabric hinge 30 or by any other suitable means.

As shown more clearly in Figs. 2 and 3, the clamping members A and B are provided with metal strips 1 which are preferably covered by fabric covers 2. To the metal strip

35 1 of clamping member A, the binder posts 3 may be secured in any suitable manner. In the illustration given, the strip 1 of the clamping member A is provided with an internally threaded boss 4 which receives a reduced threaded end 5 of the binder post 3. With this construction,

40 binder posts of any desired diameter may be used interchangeably, as long as the reduced end 5 engages the internally threaded boss 4.

45 The upper clamping member B is provided with openings 6 adapted to receive the binder post 3.

In order to lock the upper member B upon the binder posts, I prefer to employ the following construction. As illustrated more

clearly in Figs. 2 and 3, a plate member 7 is secured to the top wall of the clamping member B near each end by any suitable means, such as, for example, rivets. Near one of the ends of plate 7, a portion of the metal is struck upwardly to form a pivot support 8, while at the same time providing an opening 9 through which the binder post 3 may extend. As shown more clearly in Fig. 4, the pivot standard 8 is provided with shoulders 10 adapted to carry a slotted locking bar 11. A cap 12 confines the locking bar against the shoulders 10 but allows sufficient play to permit the bar 11 to rock upon the shoulders 10 as a pivot. The forward end 55 of the locking bar 11 is provided with an opening 13 adapted to receive one of the binder posts 3.

In order to maintain the locking bar 11 in engaged and disengaged positions, I prefer 60 to employ a metal spring strip 14, in substantially the shape illustrated. Preferably the spring 14 comprises a forwardly extending arm 15 engaging the under side of the locking bar 11 and a curved, vertical strip 16 65 adapted to engage the rear end of the locking bar. The spring 14 is also preferably provided with a rearwardly-curved upper portion 17 which serves as a means for locking the rear end of the bar 11 in raised and 70 lowered positions. With the form of spring 75 illustrated, the portions 16, 17 together resemble somewhat the letter S.

Any suitable means may be used to secure the spring to the plate 7. In the illustration 80 given, a rivet is used.

In the operation of the device, the locking member may be caused to assume the position shown in Fig. 2 by drawing back the vertical spring portions 17 and 16 so as to 85 permit the forwardly extending spring arm 15, which normally urges the lever 11 upwardly, to raise the rear end of lever 11. In this position, the locking member 11 is held against the binder post 3 and prevents upward movement of the clamping member P. When it is desired to unlock the members, the rear end of the lever 11 may be depressed 90 so as to swing the locking bar or lever to a substantially horizontal position. In this 95 100

position, the member B may be raised or lowered freely along the binder posts. The horizontal position of the lever 11 is maintained against the upward pressure of spring arm 5 15 by the curved end portion 17 of spring 14.

In the above construction, it will be observed that the spring 14 serves not only to urge the locking bar 11 into locking position but also it serves to maintain the locking bar 10 firmly in either locked or unlocked positions.

The locking structure is extremely simple, sturdy and effective in operation.

If desired, the upper ends of the posts 3 may be provided with squared-off indentations 18 adapted to receive a wrench or tool 15 for turning the posts 3 when it is desired to remove them or to insert them into the threaded bosses 4.

While I have described a specific locking 20 mechanism, it is obvious that the details of construction may be changed without departing from the spirit of my invention.

The foregoing detailed description has been given for clearness of understanding 25 only, and no unnecessary limitations should be understood therefrom, but the appended claims should be construed as broadly as permissible, in view of the prior art.

I claim:

30 1. A post-binder comprising, a post, a clamping member movably fitted thereon, a locking member apertured at one end to receive said post, means for pivotally supporting said locking member on said clamping

35 member, spring means for urging said locking member into contact with said post, and a releasable spring catch adapted to hold said locking member out of engagement with said post.

40 2. A post-binder comprising, a post, a clamping member movably fitted thereon, a locking member apertured at one end to receive said post, means for pivotally supporting said locking member on said clamping 45 member, spring means for urging said locking member into engagement with said post, and a spring catch cooperating with said spring means to releasably hold said locking member out of engagement with said post.

50 3. A post-binder comprising, a post, a clamping member movably fitted thereon, a locking member apertured at one end to receive said post, means for pivotally supporting said locking member on said clamping 55 member, spring means for urging said locking member into engagement with said post, and a spring member equipped with a cam portion adapted to releasably hold said locking member in engagement and out of engagement with said post.

60 4. A post-binder comprising, a post, a clamping member movably fitted thereon, a locking member apertured at one end to receive said post, means for rockably supporting said locking member on said clamping

member, spring means urging said locking member into contact with said post, and a retractable spring member adapted to engage the rear end of said locking member and to releasably maintain it in unlocked and locked 100 positions.

5. A post-binder comprising, a post, a clamping member movably fitted thereon, a plate secured to said clamping member, said plate having a portion struck therefrom to 75 form a pivot support, a locking lever member pivotally engaging said support and apertured at one end to receive said post, spring means adapted to urge said lever into contact with said post, and a spring catch 80 adapted to hold said locking member out of engagement with said post.

6. A post-binder comprising, a post, a clamping member movably fitted thereon, a plate secured to said clamping member, said 85 plate being provided with a pivot support, a lever fulcrumed on said support and apertured at one end to receive said post, and a spring secured to said plate member and provided with a spring arm adapted to 90 urge said lever into engagement with said post, said spring being also provided with a spring arm adapted to releasably hold said lever out of engagement with said post.

7. A post-binder comprising, a vertical 95 post, a clamping member movably fitted thereon, a plate member secured to said clamping member and having a portion struck therefrom to provide a pivot support, the opening thus formed being adapted to receive said post, a lever member pivotally carried by said support and provided at one end with an aperture adapted to receive said post, and a spring secured to said plate and provided with a forwardly extending arm adapted to urge the rear portion of said lever in an 100 upward direction.

8. In combination with a post-binder equipped with a post and a clamping member movably fitted thereon, a locking member provided with an aperture adapted to receive said post, means for pivotally supporting said locking member on said clamping member, and a spring member equipped with an arm adapted to urge said locking member into engagement with said post and equipped also with a spring catch member adapted to 110 releasably hold said locking member out of engagement with said post.

HENRY E. OLSEN.
